ATTORNEY

UNITED STATES PATENT OFFICE.

ANTON M. GUNDERSON, OF IRONWOOD, MICHIGAN.

WINDOW-SASH HOLDER.

Application filed November 22, 1927. Serial No 225,075.

My invention relates to means to be ap-
piled to a window frame and positioned in
a manner to hold the window sash raised.

The general object of my invention is to
5 provide a simple and practical device for the
indicated purpose and which is efficient in
holding the sash.

Reference is to be had to the accompanying
drawings forming part of this specification,
10 it being understood that the drawings are
merely illustrative of one example of the in-
vention.

Figure 1 is a perspective view of a window
sash holder embodying my invention illus-
15 trating the same in use on a window shown
in part;

Figure 2 is a face view of the window sash
holder;

20 Figure 3 is an edge view of my device ap-
plied, a portion of a window conventionally
indicated in section; and

Figure 4 is a horizontal section on the line
4—4 of Figure 2.

In carrying out my invention in practice
25 in accordance with the illustrated example,
a strip 10 usually of metal in practice is
formed with a vertical slot 11, and the upper
and lower ends of such strip are thickened to
form broad flanges 12 at the back or inner
30 side of the strip. Said flanges receive screws
13 or equivalent fasteners. When the strip
is secured in place the flanges serve to posi-
tion the strip with a vertical clearance space
14 at the back for the sash holding means
35 next referred to.

A turnable element 15 is formed at the in-
ner side with a shoulder 16 and is held by
pivot means including an enlarged head 17
movable in clearance space 14, and a shank
40 18 movable in slot 11. Said shank extends
through holder element 15 and has an upset
head 19 to hold the parts assembled.

With the above described device, assum-
ing the strip 10 to be secured to a window
45 frame A vertical along the jamb thereof, the
sash *a* may be held raised to the desired ex-

tent by the element 15. The said element 15
is adapted to move up or down along slot 11.
It is only necessary to raise the element 15
to the desired point according to the extent 50
to which the window is to be maintained
raised, and said element is turned so that an
end thereof is disposed beneath the sash *a*.
The weight of the window on the inner end
of element 15 causes the outer end having 55
shoulder 16 to bind against the side of the
strip 10 thereby holding the window raised.

I would state furthermore that while the
illustrated example constitutes a practical
embodiment of my invention, I do not limit 60
myself strictly to the exact details herein il-
lustrated, since, manifestly, the same can be
considerably varied without departure from
the spirit of the invention as defined in the
appended claims.

65 I claim:

1. A sash holding means, including a strip
adapted to be secured vertically on a window
frame, and a sash holding element movable
along said strip and vertically rockable, said 70
sash holding element having a lateral mem-
ber adapted to bind against said strip at the
side edge thereof when said element is pro-
jected beneath the window sash.

2. A window sash holder, including a strip 75
adapted to be secured vertically to a window
frame and having a vertical clearance space
at the back, a pivot having an enlarged head
movable in said clearance space, a shank ex-
tending outwardly from said head and mov- 80
able along said strip, and an element verti-
cally rockable on said shank, one end adapted
to be projected beneath a window sash and
having at a point outward of the said shank
a lateral member presenting a shoulder 85
adapted to bind against said strip.

Signed at Ironwood, in the county of
Gogebic and State of Michigan, this 14th
day of November, A. D. nineteen hundred
and twenty-seven.

ANTON M. GUNDERSON.
